[57] CLAIM

The ornamental design for a circular pocket with bag portion, as shown and described.

DESCRIPTION

FIG. 1 is a top plan view of a circular pocket with bag portion attached to at least a portion of a bag and illustrated with an access shown in broken lines;

FIG. 2 is a bottom plan view thereof from which only the portion of the bag is viewable;

FIG. 3 is a bottom elevational view thereof;

FIG. 4 is a left side view thereof, the right side view being a mirror image;

FIG. 5 is the top plan view of FIG. 1 of a particular embodiment in which the circular pocket comprises a top-accessed circular pocket; and,

FIG. 6 is a left side view of the embodiment of FIG. 5, the right side view being a mirror image.
